United States Patent Office

Des. 207,102
Patented Mar. 7, 1967

207,102

CHAIR

Lyle C. Hennessey, Longmont, Colo.
(5032 Kearsarge, Los Alamitos, Calif. 90720)

Filed Mar. 4, 1966, Ser. No. 1,294

Term of patent 14 years

(Cl. D15—1)

Fig. 1

Fig. 2

Fig. 3

Fig. 4

Fig. 5

Fig. 6

FIGURE 1 is a perspective view of a chair showing my new design;

FIGURE 2 is a front elevational view;

FIGURE 3 is a top plan view;

FIGURE 4 is a side elevational view;

FIGURE 5 is a rear elevational view; and

FIGURE 6 is a view taken on line 6—6 in FIGURE 4.

The side opposite from that shown in FIGURE 4 is a reverse duplicate thereof.

I claim:

The ornamental design for a chair, as shown and described.
